UNITED STATES PATENT OFFICE

2,023,671

SHOE CONSTRUCTION

August G. Eichhorn, St. Louis, Mo., assignor, by
mesne assignments, to Perma Corporation, Chi-
cago, Ill., a corporation of Illinois

Application April 8, 1932, Serial No. 603,995

16 Claims. (Cl. 36—24.5)

This invention relates to foot apparel manu-
facture and more particularly to the heel con-
struction thereof.

Foot apparel, as now manufactured, has the
5 heel secured to the heel seat of the shoe by means
of nails, by means of screws and even by bolts,
and in either instance the breakage of wooden
heels, such as are used on women's shoes, is con-
siderable, it slows up production and results in
10 unnecessary expense to this operation in the
manufacture of shoes.

It is therefore one of the primary objects of
this invention to provide novel means fixed to
15 the heel seat of a shoe and provided with means
receivable in recesses formed in the base of the
heel, and also, the provision of means carried by
the heel and engaging the means receivable in
the heel recesses for securely holding the heel
20 to the heel seat of the shoe by drawing the base
of the heel seat into tight contact with the heel
seat of the shoe and holding it there.

Another salient object of the invention is to
provide novel means for detachably securing a
25 heel to the heel seat of a shoe.

A further object of the invention is to pro-
vide the heel seat of foot apparel, such as
shoes, with a plate by means of suitable fasten-
30 ing devices and with portions of the plate extend-
ing into heel recesses formed in the base of the
heel where such plate portions are fastened by
independent means for securely locking the heel
to the heel seat of the shoe.

A further object of the invention is generally
35 to improve the heel construction of foot ap-
parel.

A still further object of the invention is the
provision of a heel construction for shoes, which
possesses advantages in point of simplicity, elimi-
40 nates breakage of wooden heels in the applica-
tion thereof to the heel seats of shoes, and, at
the same time proves itself comparatively inex-
pensive in the cost of manufacture and especially
so in the application of the heel to the shoe.

45 With the above and other objects in view, the
invention consists in the novel application of
heels to shoes, construction, arrangements, com-
binations and formation of parts, as will be here-
inafter more fully described, claimed and illus-
50 trated in the accompanying drawing, in which
drawing:

Fig. 1 is a view of the heel seat portion of a
shoe and particularly illustrating the heel attach-
ing plate fixed to the heel seat of the shoe.

55 Fig. 2 is a view, in side elevation, of the heel

seat portion of a shoe with the heel attaching
plate fixed thereto.

Fig. 3 is a view illustrating the manner of se-
curing a heel to the heel seat of a shoe and em-
bodies the features of this invention. 5

Fig. 4 is a top plan view of a shoe heel illustrat-
ing the recesses formed in the base thereof.

Fig. 5 is a side elevation of the heel attaching
plate.

Fig. 6 is a front elevation of the heel attach- 10
ing plate, with a portion thereof broken away.

While this invention relates generally to foot
apparel, and particularly to an improved heel
construction for shoes, the same has been illus- 15
trated as including a wooden heel for ladies' 15
shoes, but it is to be understood that the same
is applicable to men's children's shoes, as well.

In the drawing, A designates a part of the heel
portion of a shoe, and includes the outsole B, the
insole C, and the heel seat of the shoe which is 20
formed by the trimmed heel portion D of the out-
sole B to reduce its thickness and the turned
under portions of the upper, the counter and the
lining of the shoe, which is designated generally
as E, and, which is like heel seats in the present 25
shoe construction, excepting that the heel portion
of the outsole in this case fills the entire heel
seat cavity of the shoe.

In carrying out the aim of the present inven-
tion, a suitable plate 1 is employed, preferably 30
metallic. The plate 1 is applied to the trimmed
heel portion D, of the outsole B and to the mar-
ginal edge of the turned under edge portion E of
the heel seat of the shoe. The plate 1 has the
35 general outline of the heel seat of the shoe and
shaped to the contour thereof by being longitudi-
nally and transversely curved, as shown in Figs.
5 and 6, and it is secured to the heel seat of the
shoe by means of suitable fastening devices 2, 40
which fastening devices, as shown, are integral
parts of the plate 1 and punched therefrom in
the form of prongs, which pass through the heel
portions of the outsole and insole and into which
insole the prongs are clinched in any well known
45 manner to prevent displacement of the plate 1 on
the heel seat of the shoe. Fastening devices in
the form of nails may be used, if desired, in fas-
tening the plate 1 to the heel seat of the shoe.

A plurality of suitable keepers or ears desig- 50
nated 3 and 4 are formed on the plate 1 and di-
rected downwardly therefrom at approximately a
right angle thereto. The keepers or ears 3 and 4
are spaced a suitable distance apart from each
other and each is provided with a lock pin open- 55
ing 5. The apertured keepers or ears 3 and 4

are shown as disposed transversely of the plate 1 so as to lie transversely of the heel seat of the shoe. The front keeper or ear 4 may be longer than the rear keeper or ear 3, as it assumes a front position on the plate 1 and a like position relative to the shoe heel.

The heel to be applied to the heel seat of the shoe, is a one-piece heel designated 6, and it is shown in the drawing as in the form and shape 10 of an ordinary wooden heel for ladies' shoes. The usual base or heel seat surface 7 of the heel 6 is provided with a plurality of transversely disposed narrow slotted relatively shallow recesses 15 designated 8 and 9, and these recesses enter the heel a distance equal, or better than the lengths of the keepers 3 and 4, respectively, of the plate 1. The recesses 8 and 9 of the heel 6 are of such dimensions as to cause the keepers 3 and 4 to engage the walls thereof when the heel 6 is applied to the heel seat of the shoe, as clearly shown in Fig. 3.

The heel 6 is provided with a bore or opening 16 of uniform dimension throughout its length 18, which opening is directed into the heel from the breast 11 thereof a short distance below the heel seat surface 7 thereof. The opening 16 is so positioned that when the heel is applied with the desired pressure to the heel seat of the shoe, that it will register with the openings 5 in the keepers or ears 3 and 4, and at which time a suitable lock-pin 12 is forced into the heel opening 16 so as to pass through and frictionally engage in the openings 5 of the plate ears 8 and 9 for holding the heel in a locked position on the heel seat 35 of the shoe and against displacement thereon.

When the heel 6 is applied, in the manner shown, to the heel seat of the shoe, the heel is securely held to the heel seat of the shoe. If desired, glue may also be employed when attaching the heel to the shoe heel seat. This is desirable when the heel is not to be detachable. When it is desired to have the heel readily detachable from the heel seat of the shoe, the breast 11 of the heel 6 adjacent the outer end of the lock-pin opening 16 is enlarged, or recessed, as at 13 so that the outer end of the lock-pin 12 may be easily grasped by means of a suitable extracting tool, as is manifest, for withdrawing the lock-pin 12 from the opening 16 and the openings 5 of the keepers or ears 3 and 4.

When the heel 6 has been applied, as described, to the heel seat of the shoe, the usual breast leaf 14, which is a part split from the outsole B is applied to the breast 11 of the heel 55 6, in the usual manner, and it conceals the outer end of the lock-pin 12 and the breast recess 13 from view. If the shoe heel is to be detached, for any reason, the breast leaf 14 will first have to be removed from the breast of the heel, as is manifest.

Due to the fact that the trimmed heel portion of the outsole extends beyond the juncture of the shank therewith and fills the heel seat cavity within the edge of the turned under upper, counter and lining portions of the shoe, weakness at the juncture of the heel portion of the outsole with the shank portion thereof is obviated, and the improved shoe is greatly strengthened at this point where ladies' shoes, in particular are generally rather weak, and, therefore the tendency of the outsole to be broken at the front edge of the heel is eliminated.

The heel 6 can be applied to the heel seat of a shoe by hand, or it can be applied thereto by a machine, the latter where increased production

is required and at less cost than by hand and less than applying wood heels to ladies' shoes by the present method.

The many advantages of the herein-described invention will readily suggest themselves to those 5 skilled in the art to which it appertains.

From the foregoing description, it is evident that a simple device for the purpose has been disclosed, but it is to be understood that I do not desire to restrict, or limit myself to the very 10 details of the invention shown and described, which is merely illustrative, it being obvious that changes, not involving the exercise of invention, may be made without conflicting or departing from the spirit of the invention within the scope 15 of the appended claims.

What I claim is:

1. A shoe construction, having, in combination, a heel seat including the trimmed heel portion of an outsole and the turned under portions of 20 the counter, upper and the lining of the shoe, a plate shaped to conform to the shape of the heel seat, means for securing said plate to the heel seat, a wooden heel having transverse recesses communicating with the base of the heel and provided with an opening directed from the breast of the heel and communicating with said heel recesses, means directed from said plate and receivable in said heel recesses, and means receivable in said heel opening passable through aligned 25 openings in the means directed from said plate for securing the heel to the heel seat of the shoe and against displacement thereon.

2. In combination with a shoe comprising an upper including a counter, an outsole, an insole 35 and a shank, the outsole having its heel portion trimmed to the desired shape and size which together with the insole and turned under edge of the counter forms the heel seat of the shoe, of a plate shaped to conform to the contour of 40 the heel seat of the shoe, fastening means integral with the plate for securing the plate in position on the heel seat of the shoe and clinchable to the insole, a heel having a pair of spaced transverse slotted recesses within the body of 45 the heel and open only to the heel seat surface of the heel, flat fastening means integral with and directed downwardly from the plate receivable in the slotted recesses of the heel, and locking means carried by the heel and insertable 50 through a breast opening therein for interconnecting the fastening means on the plate for securely locking the heel against displacement on the heel seat of the shoe.

3. In combination with a shoe having a prepared heel seat, a plate shaped to conform to the contour of the heel seat and of less dimensions than the heel seat, fastening means for securing the plate to the heel seat of the shoe, spaced flat members integral with and directed 60 downwardly from the plate, a heel having spaced slotted recesses directed into the heel from the heel seat surface thereof to receive said flat members, and locking means carried by the heel and insertable thereto from the breast thereof 65 for interconnection with the spaced flat members adjacent the heel seat surface of the heel for holding the heel against displacement on the heel seat of the shoe.

4. In combination, a shoe having a prepared 70 heel seat, a plate shaped to conform to the contour of the heel seat but of less size than the heel seat, flat apertured keepers integral with and directed downwardly at a right angle to the plate, anchoring devices clinchable to a shoe in- 75

sole for securing the plate in position on the heel seat of the shoe, a heel having spaced slotted recesses in the heel seat surface thereof to conform to the shape of the keepers and to receive 5 the flat apertured keepers, and a lock-pin insertable into the heel from the breast face thereof of adjacent the upper end of the heel for interconnection with the keepers.

5. In combination with a shoe having a portion 10 of the outsole of the shoe forming a part of the heel seat of the shoe, of a dished plate peripheral- ly shaped to conform to the outline of the heel seat of the shoe, said plate including pointed fastening means for securing the plate to the 15 heel seat of the shoe and including flat aper- tured ears directed downwardly from the plate so as to enter relative shallow slotted recesses in a heel to be applied to the plate and heel seat of the shoe, said heel having a breast opening 20 near the upper end thereof and a lock-pin insertable into said breast opening for intercon- necting the flat apertured ears of the plate re- ceivable in the heel recesses.

6. In combination with a shoe having a portion 25 of the outsole of the shoe forming a part of the heel seat of the shoe, a longitudinally and transversely curved plate fixed to the heel seat of the shoe, a pair of spaced parallel flat ears each having an opening directed downwardly 30 from the plate and said ears having their edges curved, a heel having a heel seat surface and having a pair of recesses formed in the heel seat surface of the heel shaped to receive said ears, and a locking pin insertable into a breast opening 35 in the heel near the upper end thereof for inter- connection with said ears for locking the heel to the shoe.

7. In combination with a lady's shoe having a prepared heel seat which includes a trimmed 40 section of the outsole, a wooden heel having a heel seat surface to conform to the contour of the heel seat of the shoe and provided with a pair of transverse slotted recesses directed into the heel a short distance from the heel seat surface 45 thereof and a plate shaped to conform to the contour of the heel seat and the contour of the heel seat surface of the heel fixed to the heel seat of the shoe, flat apertured ears having curved edges depending from said plate and receivable in the heel seat surface recesses of the heel, and a pin insertable into the heel below and adjacent the heel seat surface thereof for interconnecting said ears to hold the heel against displacement on the shoe.

55 8. A heel for shoes having a dished base pro- vided with suitably spaced parallel arranged elongated shallow recesses disposed transversely of the heel and directed into the heel at sub- stantially right angles to the plane of the shoe 60 heel base, and said heel having a bore of uniform cross-sectional area throughout its length di- rected into the heel and intersecting the re- cesses above the lower edges thereof, and said bore being disposed in close proximity to the base of the heel and in parallel relation to the plane thereof.

9. In a lady's shoe construction, a shoe having a heel seat to which a heel is to be applied and said heel seat being formed by the heel portion 70 of the insole, the turned under edge of a counter and a trimmed portion of an outsole, a concaved-convexed pronged plate secured to the heel seat of the shoe by means of the prongs of said plate penetrating the heel seat material and clinched 75 to the heel portion of the insole, a pair of spaced

flat apertured ears having curved edges formed integral with and transversely of the plate and receivable in longitudinally alined slotted recesses so shaped in the heel seat surface of the heel as to conform to the shape of said ears, said heel having a breast opening interconnecting the slotted recesses in the heel, and a lock-pin insertable into the breast opening of the heel for interconnection with the apertured ears of said plate and the outer end of said pin being con- 10 cealed by the breast covering of the heel which is an integral part of the outsole of the shoe and split therefrom.

10. A plate of the class described comprising a sheet metal plate shaped to conform to the con- 15 tour of the heel seat surface of a shoe, said plate including a plurality of spaced pointed fastening elements directed upwardly from the edge of the plate, and said plate including a pair of down- 20 wardly directed flat apertured ears formed in- tegral therewith, one of said ears being at the forward edge of the plate and the other of said ears being disposed to the rear of said first ear and formed by a cut-out portion of the plate.

11. A plate of the class described comprising a sheet metal plate shaped to conform to the con- 25 tour of the heel seat surface of a shoe, said plate including a plurality of spaced pointed fastening elements directed upwardly from the edge of the plate, and said plate including a pair of down- 30 wardly directed flat apertured ears formed in- tegral therewith, one of said ears being at the forward edge of the plate and the other of said ears being disposed to the rear of said first ear and formed by a cut-out portion of the plate and 35 both of said ears having a curved edge.

12. In a shoe construction, the combination of a heel attaching plate having anchoring means to penetrate the heel seat material of the shoe from the lower side thereof and clinchable to the 40 heel portion of the insole of the shoe, keepers on the plate, a heel having recesses directed into the base thereof and receiving the keepers, and a pin entering the heel adjacent the base there- 45 of and insertable through the keepers to hold the heel in a locked position on the heel seat of the shoe.

13. In combination with a shoe having a heel seat and a heel, attaching means for securing the heel to the heel seat of the shoe, said at- 50 taching means comprising a longitudinal and transversely concaved-convexed metal plate of a size to leave a marginal border between the edge of the plate and the edge of the heel seat when attached thereto and having prongs for pene- 55 trating the heel seat material and clinchable against the upper face of the insole of the shoe, the plate having a pair of closely spaced parallel arranged ears having aligned openings for in- 60 sertion into correspondingly spaced slotted re- cesses in a shoe heel for the attachment of the heel to the plate by means of a securing pin introduced into an opening in the heel and the aligned openings in the ears on the plate in close 65 proximity to the base of the shoe heel.

14. A shoe heel attaching device comprising a metal attaching plate longitudinally and trans- versely curved downwardly to correspond to the heel seat of a shoe and the base of a heel adapted to be permanently and rigidly attached to the 70 heel seat of the shoe by integral prongs directed upwardly from the edge of the plate and to pro- vide a marginal area between the edge of the plate and the edge of the heel seat, a pair of spaced apertured ears depending from the plate, 75

- the shoe heel having base recesses adapted to receive said apertured ears, and means in the form of a locking-pin introduced into a bore in the heel and arranged to extend through the apertured ears in close proximity to the base of the heel so as to cause the peripheral edge of the base of the heel to be held rigidly against the outer edge portion of the heel seat area of the shoe beyond the peripheral edge of the heel attaching plate.
15. A shoe comprising a heel seat, a heel attaching plate permanently secured to the heel seat by a plurality of marginal prongs penetrating and clinched to the insole of the shoe, said plate having apertured ears directed oppositely from the prongs, a heel having base recesses applied to the heel seat of the shoe with the ears receivable in the slotted recesses in the heel, and a pin forced into an opening adjacent the base

of the heel and insertable through the apertured ears for frictionally locking the pin in position for securely holding the heel on the heel seat of the shoe and locking it against displacement thereon.

16. In combination with a shoe having a heel seat and a heel therefor, means for permanently securing the heel to the heel seat, said means comprising a plate corresponding in shape to the heel seat and the base of the heel and of a size 10 smaller than the heel seat and base of the heel and having means including a pin for securing the heel to the plate, the plate having marginal pronged fasteners to penetrate the heel seat material and clinchable to the inner face of the insole of the shoe, said fasteners being at the edge of the plate and arranged in three pairs, front, rear and intermediate.

AUGUST G. EICHHORN.
